OIL CIRCUIT BREAKER

Svend Barfoed, San Francisco, Calif.

Substitute for application Serial No. 480,874, September 10, 1930. This application August 13, 1934, Serial No. 739,583

10 Claims. (Cl. 200—150)

This invention relates to oil circuit breakers particularly intended for use in alternating current circuits, the present application being a substitute for my former application Serial Number 5 480,874, entitled "Oil circuit breaker", filed September 10, 1930.

There are several forms of oil circuit breakers now in use and generally the arrangement consists of a pair of stationary contacts and a pair of 10 movable contacts mounted to separate or close in a vertical direction through the oil.

When opening such a circuit breaker, an arc is drawn between each pair of stationary and movable contacts and an arc's position will, at the 15 beginning of the stroke, be nearly stationary in the path of the moving contact; the oil vaporizes and gasifies to form a large bubble which will be inefficiently cooled since the surrounding oil must flow towards it from rest by convection. Upon 20 further movement of the contacts, the electrodynamic force of the current flowing in the arc comes more into play to move or bend out the arc to enlarge its loop. This bending of the arc will tend to cool it chiefly in its middle region.

Both contacts and the ends of the arc will still be 25 inefficiently scoured and cooled by the oil; the upper contact, because it is stationary, and the lower or moving contact, because of cavitation pockets formed in the oil by its movement through the oil; therefore, the arc will maintain itself a comparatively long time from the continued ion production from the hot contacts and from the hot gas bubble at the ends of the arc where its position is nearly stationary with respect to the arc.

The path taken by the contacts in passing 30 through the oil, the amount of cavitation produced, the action of the electrodynamic force around the arc, and the speed of operation are accordingly important factors. It is further to be carefully noted that in dealing with alternating 35 currents, the power of a single phase supply is pulsating due to the sinusoidal variation in current and voltage with respect to time and the fact that in an oil circuit breaker the arc tends to go out when the current is at or near zero value. The heat wave generated by the pulsating power in each successive half cycle will produce, in like manner, pulsating quantities of gases and vapors from the contact materials and decomposition 45 products of the oil.

The object of the present invention is to generally improve and simplify the construction and 50 operation of circuit breakers of this character; to provide a circuit breaker in which the contacts can be separated at a high rate of speed; to pro-

vide contacts which present a minimum area to the path of travel through the oil so as to reduce resistance of movement to a minimum and to substantially eliminate cavitation and undue agitation of the oil; to provide a pair of contacts which are pivotally mounted and movable in unison on arcs away from each other so as to pull or move the arc downwardly and horizontally through the oil during the breaking operation; to provide contacts which are divided into widely spaced 10 pairs of main contacts and each pair having an intermediate auxiliary contact to carry the arc during the breaking operation; to provide a barrier to confine the arc between the auxiliary contacts during the breaking operation; to form 15 pockets in the barrier to contain oil in such quantities as to become instantaneously vaporized by the heat of the arc as it sweeps over the same and thereby cause a series of explosions tending to disperse or blow out the arc; and, further, to provide means for deflecting and directing oil over the faces of the auxiliary contacts and between the same to reduce burning and to break up and further quench the arc.

The circuit breaker is shown by way of illustration in the accompanying drawings, in which—

Fig. 1 is a side elevation of the oil circuit breaker, said view being partially in section and showing the switch or contact operating mechanism;

Fig. 2 is an enlarged central vertical section of the oil circuit breaker;

Fig. 3 is an enlarged central section of the barrier member, said view also showing different positions assumed by the contacts during separation thereof;

Fig. 4 is a cross section taken on line IV—IV of Fig. 3;

Fig. 5 is a view similar to Fig. 3, showing the connecting links whereby the contact arms are actuated; and

Fig. 6 is an end view of Fig. 5.

Referring to the drawings in detail and particularly Figs. 1 and 2, A indicates a tank or similar container provided with a bottom section 2 and a 45 cover section 3. Supported by the cover section and extending therethrough are a pair of insulating bushings such as indicated at 4 and 5 and extending through the bushings are conductor bars 6 and 6a on the lower ends of which are 50 pivotally mounted, as at 7 and 8, contact or switch arms 9 and 10. The lower ends of the arms, see Figs. 3, 4 and 6, are fork-shaped to form a pair of main contacts 11. These contacts are widely separated so that they may straddle a barrier 55

member generally indicated at 12. The central and lower end of each arm is provided with a deflector plate 13. The sides of the deflector plates are carried downwardly, as shown at 14, 5 and they form bearings for a pair of auxiliary contacts generally indicated at 15 and 16. These contacts are pivoted between the bearing lugs 14 and are free to move about the pivots to a limited degree, the amount of pivotal movement being 10 determined by stop lugs 16a. The auxiliary contacts are urged to a position where the stop lugs 16a stop their movement by springs such as indicated at 17. The function of the deflecting plates 13 and the yielding action of the auxiliary 15 contacts will hereinafter be described.

The barrier member indicated at 12 may be constructed of any suitable insulating material and it is supported with relation to the bottom section 2 by means of a pedestal insulator such as 20 shown at 18. The barrier member in side elevation is substantially wedge-shaped. A groove 19 is formed in each side of the upper face of the barrier member and these grooves are connected by a center slot 20, the adjacent faces of which 25 are grooved as shown at 21 to form successive superposed cylindrical pockets for the reception of oil, as will hereinafter be described. The main function of the barrier block is to confine the arc formed between the auxiliary contacts during 30 separation thereof or breaking of the circuit and it also functions to disperse or blow out the arc, as will hereinafter be described. In addition thereto, it carries a pair of contact members 22 which are engaged by the main contact arms 11 35 when a circuit is closed.

In the operation of a switch or circuit breaker of this character, it is essential that the separating action of the contacts shall be as rapid as possible. Means must accordingly be provided 40 whereby rapid separation or opening of the contacts may be accomplished. The operating mechanism employed in the present instance is best illustrated in Figs. 1 and 2. It consists of a pair of links 25 pivotally connected at their lower ends 45 to the respective contact arms 9 and 10, as shown at 26, and pivotally connected at their upper ends, as shown at 27, to a plunger bar 28. The upper end of the plunger bar, see Fig. 1, is connected with a lever 29 pivoted as at 30. The opposite end 50 of this lever is connected with a connecting rod 31 which, in turn, is pivotally connected to a crosshead 32 and a piston 34 which operates a cylinder such as shown at 35. This cylinder is provided with a pair of three-way valves such as 55 shown at 36, which are connected with a suitable source of fluid supply through means of a pipe 37 and which is also provided with a discharge pipe 38. The source of fluid supply is maintained at a predetermined pressure so that the speed of 60 the piston 34 and the contact arms 9 and 10 may be determined, this being of considerable importance, as will hereinafter appear. The valves 36 are connected by common link mechanism 39 and this is in turn actuated by an operating lever 40, as shown.

In actual practice it will be understood that the container A is substantially filled with oil so as to maintain the switch mechanism and the barrier member in a submerged condition. If a 70 circuit through the breaker has been closed, the contact arms and contacts will assume the position shown in Fig. 2 and when the circuit is broken the contact arms will assume the dotted line position shown in Fig. 2. To break the

circuit it is only necessary for the operator to swing the operating lever 40 from the full line position shown in Fig. 1 to the dotted line position indicated at 40a. This reverses the position of the valves 36 and as such admits the fluid 5 under pressure to the lower side of the piston 34 and at the same time permits the fluid previously delivered to the cylinder to discharge through the upper valve 36 and the discharge pipe 38 and, as the fluid employed is maintained 10 at a predetermined pressure, the speed of the piston and the mechanism actuated thereby can be determined. The operating mechanism of course performs only one function, to wit, that of separating or closing the contacts. 15

Since the circuit breaker here illustrated is particularly intended for alternating current circuits, it is to be remembered that the power of a single phase supply is pulsating due to the sinusoidal variation in current and voltage with respect to time; and for explanation unity of power factor will be assumed. In the present instance, the time required to swing the contacts from closed position to full open or separated position is known and for the purpose of description it will be assumed that while the contacts sweep over the barrier member 12, six half cycles or impulses take place. Five of these 20 pockets are illustrated, see Figs. 3 and 4. The are produced during separation of the contacts 25 is, in the present instance, confined between the auxiliary contacts 15 and 16 by means of the barrier block 12, and as these contacts align with the slots 19 and the slot 20 having the enlarged pockets 21 formed therein, the arc must 30 pass therethrough. During movement of the contacts and as the half cycle pulsations occur, maximum current flow takes place at a frequency that causes arcing through the several pockets 35 21 successively. The body of oil confined in these 40 pockets is comparatively small and the current flow and heat produced by the arc are so great that the oil contained in the respective pockets is vaporized with such rapidity as to expand with explosive action, hence tending to disperse or blow 45 out the arc. The oil pockets 21 become longer and longer as the contacts sweep downwardly over the barrier and as each body of oil explodes it tends to disperse or blow out the ionized decomposition products as the current decreases 50 to zero, making it more and more difficult for the current to reestablish the arc as the current flow again reaches maximum during each half cycle of flow.

The dispersing or blowing out action of the arc 55 just described is not the only action depended upon to quench the arc. For instance, by referring to Fig. 3, it will be noted that the deflecting plates 13 are provided. These will, during the downward and outward sweep of the contact 60 arms, function as nozzles and discharge oil under high velocity downwardly over the faces of the auxiliary contacts and between the same in the direction of the arrows indicated at a. The high velocity of the oil is obtained by the rapid motion of the contact arms in an outward direction and the oil thus delivered over the faces of the auxiliary contacts and between the same is depended upon to reduce any burning action and the formation of vapors which would tend to sustain the arc. In the present structure the current contacting leads passing through the insulators 4 and 5 and the arms 9 and 10 form a loop in which current flows. Such a loop is subject to an electrodynamic force tending to enlarge it on 70 75

the well known principle of electromagnetism. When the contact arms separate and the arc is struck, the same electrodynamic force is also active on the arc due to the current flowing through it and the arc is thereby enlarged, curved and propelled in a downward direction, as indicated by the dotted line *b*. This is another reason for directing the oil jets in the direction of arrows *a*; see Fig. 3, as the oil so directed is projected with high velocity against the arc formed between the contact members and in the same direction as the electrodynamic force relative to the arc, thus tending to further enlarge and expand the arc to cause disruption thereof.

Also it should be noted that the contact arms sweep downwardly and outwardly about the pivots *7* and *8*. This is also important as it rapidly increases the spacing between the contacts, thereby lengthening the arc, and as the contacts at the same time move downwardly, there is a tendency to pull the arc into a body of fresh cool oil, this action being exceedingly important as it rapidly cools the arc core and, furthermore, interposes a larger and larger body of oil, the resistance of which soon becomes too great for the arc to penetrate.

Another important feature to be considered is the forking of the main contact arms at their lower ends to form a pair of main contacts *11* on each arm. These contacts are widely separated and are disposed on opposite sides of the barrier member *12*. These contacts, when in engagement with the stationary contact blocks *22*, carry the main current flow when a circuit is established. They are held in engagement with the contact blocks *22* with pressure due to the upward pull on the links *25*. When the contact arms are brought together to close the circuit, the auxiliary contacts first engage and, as they are pivotally and yieldingly supported between the bearing lugs *14* by means of the springs *17*, they will give until the main contacts *11* engage the contact blocks *22*. During separation of the contacts when breaking the circuit, the main contacts *11* will leave the contacts *22* and will move a considerable distance before the auxiliary contacts *15* and *16* are disengaged, as they will be held in engagement with relation to each other by the springs *17* until the stop lugs *16* prevent further movement. At that point they separate and as they have been carrying the current flow during the preliminary separation of the main contacts, the arc is established between the auxiliary contacts, hence preventing arc formation between the main contacts. Burning action, if any, will accordingly take place between the auxiliary contacts, leaving the main contacts unaffected. Another important feature to be considered is the fact that the main contacts present a comparatively small area when passing through the oil, as they are substantially knife-like in formation, hence cutting through the oil during the rapid movement of the contact arms without producing any material agitation or cavitation in the oil. This is obviously desirable as it is cavitation more than anything else that tends to continue arcing.

While certain features of the present invention are more or less specifically described, I wish it understood that various changes may be resorted to within the scope of the appended claims. Similarly, that the materials and finishes of the several parts employed may be such as the manufacturer may decide, or varying conditions or uses may demand.

Having described my invention, what I claim and desire to secure by Letters Patent is—

1. In a circuit breaker of the character described, a container for oil, a pair of pivotally mounted arms submerged in the oil, a pair of spaced main contacts on each arm, an auxiliary contact on each arm and disposed between the main contacts, means for imparting movement to the arms about their pivots to separate the contacts, means whereby the auxiliary contacts are maintained in engagement until a substantial separation between the main contacts has taken place, and a pair of barrier plates disposed in the container in a position where the main contacts will move parallel to the said plates while the auxiliary contacts will move along the edges of the plates and the arc formed during the separation of the auxiliary contacts will be confined between the plates and the auxiliary contacts.

2. In a circuit breaker of the character described, a container for oil, a pair of pivotally mounted arms submerged in the oil, a pair of spaced main contacts on each arm, an auxiliary contact on each arm and disposed between the main contacts, means for imparting movement to the arms about their pivots to separate the contacts, means whereby the auxiliary contacts are maintained in engagement until a substantial separation between the main contacts has taken place, a pair of barrier plates disposed in the container in a position where the main contacts will move parallel to the said plates while the auxiliary contacts will move along the edges of the plates and the arc formed during the separation of the auxiliary contacts will be confined between the plates and the auxiliary contacts, and means for directing oil under high velocity between the faces of the auxiliary contacts and downwardly between the barrier plates.

3. In a circuit breaker of the character described, a pair of movable contacts, a barrier member cooperating therewith, said member comprising a pair of plates constructed of insulating material spaced to form a slot for the reception of oil and the adjacent faces of the plates having spaced grooves formed therein forming successively disposed enlarged bodies of oil, and means for moving the contacts at opposite ends of the slot and exteriorly thereof so that the arc only will pass through the slot.

4. In a circuit breaker of the character described, a pair of contact members, means for moving the contact members from a closed to an open position, and a barrier interposed between the paths of movement of said contact members, said barrier being constructed of insulating material and having elongated pockets extending through it in a position to align one at a time with said contact members as they traverse their path of movement, said pockets progressing in length toward the full open position of the contact members.

5. In a circuit breaker of the character described, a pair of contact members, means for moving the contact members from a closed to an open position, and a barrier interposed between the paths of movement of said contact members, said barrier being constructed of insulating material and having elongated pockets extending through it in a position to align one at a time with said contact members as they traverse their path of movement, said pockets decreasing in cross sectional area toward the full open position of the contact members.

6. In a circuit breaker, a pair of plates constructed of insulating material and spaced to form a slot, a pair of contact members, and movable exterior of said plates from a closed to an open position in the plane of said slot and at opposite ends of said slot whereby the arc formed between said contact members will pass through the slot.
7. In a circuit breaker, a pair of plates constructed of insulating material and spaced to form a slot, a pair of contact members, movable exterior of said plates from a closed to an open position in the plane of said slot and at opposite ends of said slot whereby the arc formed between said contact members will pass through the slot, and means for directing a flow of oil through the arc.
8. In a circuit breaker, a pair of plates constructed of insulating material and spaced to form a slot, a pair of contact members, means to move said contact members from a closed to an open position in the plane of said slot and at opposite ends of said slot whereby the arc formed between said contact members will pass through the slot, and means actuated by movement of

the contact members for directing a flow of oil transversely through the arc.

9. In a circuit breaker of the character described, a container for oil, a pair of arms each having a contact member at one end, said arms being pivoted at their other ends so that when a circuit is broken the contact ends of the arms will swing away from each other in the plane of the electrodynamic force produced in the loop of the arc which is formed during the breaking of 10 the circuit, and means for directing a flow of oil into the arc and transversely thereof between the contacts in the same direction as the electrodynamic force to control and quench the arc.

10. In a circuit breaker, a pair of plates constructed of insulating material and spaced to form a slot, a pair of contact members movable exterior of said plates from a closed to an open position in the plane of said slot and at opposite ends of said slot whereby the arc formed between 20 the contact members will pass through the slot, and means for maintaining the movable contact members and the spaced plates submerged in a liquid arc quenching medium.

SVEND BARFOED. 25
